SUPPORTING ASSEMBLY FOR AN ABDOMINAL RETRCTOR BLADE

James J. Lally, 800 W. 52nd Terrace,
Kansas City, Mo. 64050

Filed Jan. 3, 1966, Ser. No. 427

Term of patent 14 years

(Cl. D83—12)

Fig. 1.

Fig. 2.

Fig. 3.

Fig. 4.

FIG. 1 is a front perspective view of the supporting assembly for an abdominal retractor blade;

FIG. 2 is a top plan view thereof;

FIG. 3 is a front elevational view thereof, with portions broken away for convenience of illustration; and

FIG. 4 is a side elevational view thereof.

The broken line illustration of the retractor blade disclosed in FIG. 1 is shown for illustrative purposes only.

I claim:

The ornamental design for a supporting assembly for an abdominal retractor blade, as shown and described.
